Attorney.

UNITED STATES PATENT OFFICE

HAROLD E. WHITE, OF BUTLER, PENNSYLVANIA, ASSIGNOR TO LAVA CRUCIBLE COMPANY OF PITTSBURGH, OF PITTSBURGH, PENNSYLVANIA, A CORPORATION OF PENNSYLVANIA

CRUCIBLE FURNACE LINING

Application filed January 3, 1929. Serial No. 330,108.

My invention relates to furnace linings, and more particularly to furnace linings especially designed for use in a crucible furnace of the well known cylindrical type.

1 In furnaces of the character specified, it has heretofore been the practice to line up the furnace with curved firebrick, for example, from six to eight curved bricks joined together edge to edge, with cement joints, to 10 form a circle, and a number of these superimposed circles with cement interposed between the complete circles constitute the built-up lining. This practice is a slow, laborious, and expensive method; and, besides, the lining when completed is of comparatively short life, due to the burning out of the cement joints.

The prime object of the present invention is to provide a lining construction comprising 20 a relatively small number of circular units or ring members, each formed of super-refractory materials of extreme temperature-resistance and of such character that they may be readily assembled in superimposed relationship within the furnace in a minimum length of time and at a minimum cost.

A further object of the present invention is to provide a furnace lining of the character specified, including a plurality of superimposed continuous ring members, with one of the ring members formed with an opening or a plurality of openings extending through the circular body for the purpose of receiving a burner or the like, and for providing 35 a slag opening for the lining.

Other advantages will become apparent from the specification taken in connection with the accompanying drawings, wherein:

Fig. 1 is a vertical sectional view of a crucible furnace embodying my improved lining;

Fig. 2, a sectional view on the line II—II of Fig. 1;

Fig. 3, a sectional view on the line III—III of Fig. 1, particularly showing the location of the burner and the slag openings; and

Fig. 4, a perspective view of one of the lining units.

Referring to the drawings, the crucible furnace A is of the upright cylindrical type, hav-

ing a metal casing 2, an insulating lining 3, and a bottom 4 formed of suitable refractory material.

The lining comprising my invention, as illustrated and as preferred, is designated 55 generally by the character B and, as shown, includes a plurality of circular or continuous ring units or members 5 and a member 6. Each of the said members is made of suitable highly refractory materials, having extreme 60 temperature-resisting qualities, and are of such character that they may be readily installed in the shell of the furnace by lowering the respective units from the open top of the furnace. A thin layer of cement is provided 65 between the rings only, thus producing in effect a one-piece mass lining.

As illustrated, member 6 is provided with a tangentially disposed burner-receiving opening 8 extending through the circular body and with a slag opening 9. It will be understood that these openings may be initially formed in member 6, the same being disposed in the desired positions and of proper dimensions to cooperate with the desired parts of the furnace structure.

The bottom 4 is provided with a pedestal 10 to receive the crucible C within the furnace. The furnace is closed by a refractory top 11 which is provided with a vent opening 12.

The inner diameters of the circular units 5 are uniform, forming a cylindrical combustion chamber of a predetermined size with reference to the diameter of the crucible C. The effect of such construction is to provide a smooth and uninterrupted surface for the passage of the gases of combustion. This is a decided advantage over the present constructions, which present an uneven surface, due to the great number of small units and joints comprising the lining.

It will be seen that furnaces may be relined within a minimum time by employing my lining units, thereby greatly decreasing the present expense caused by such furnaces being shut down.

I claim:

A crucible melting furnace comprising a 100 casing open at the top, a lining for the cas-

ing, said casing having a bottom supporting said lining and adapted to support a crucible, said lining comprising superposed rings of refractory material insertible through said top, one of said rings and side wall of the casing having a burner opening and a slag opening therethrough, and the rings having their bores of the same diameter and with the walls thereof in flush relation, the lining thus avoiding laterally-separable sections and affording a substantially smooth and uninterrupted surface for the passage of the gases of combustion thereover.

In testimony whereof I affix my signature.

15 HAROLD E. WHITE.
